(57) **CLAIM**

The ornamental design for a cordless chain saw, as shown and described.

DESCRIPTION

FIG. 1 is a right side perspective view of a cordless chain saw of the present invention.

FIG. 2 is a left side perspective view of the cordless chain saw according to FIG. 1.

FIG. 3 is a front view of the cordless chain saw according to FIG. 1.

FIG. 4 is a rear view of the cordless chain saw according to FIG. 1.

FIG. 5 is a right side view of the cordless chain saw according to FIG. 1.

FIG. 6 is a left side view of the cordless chain saw according to FIG. 1.

FIG. 7 is a top view of the cordless chain saw according to FIG. 1; and,

FIG. 8 is a bottom view of the cordless chain saw according to FIG. 1.
